UNITED STATES PATENT OFFICE

164,159

BAIL EAR

Norton Robson Cooke, London, England

Application October 25, 1950, Serial No. 12,727
In Great Britain April 27, 1950

Term of patent 14 years

(Cl. D58—17)

To all whom it may concern:

Be it known that I, Norton Robson Cooke, a British subject, residing at 3, Chepstow Hall, Earls Court Square, London, England, have invented a new, original, and ornamental Design for Bail Ear, of which the following is a specification, reference being had to the accompanying drawing, forming part thereof.

Figure 1 is a perspective view of a bail ear showing my new design;

Figure 2 is another perspective view thereof;

Figure 3 is a top plan view thereof;

Figure 4 is a side elevational view thereof; and

Figure 5 is a rear elevational view thereof.

I claim:

The ornamental design for a bail ear, as shown.
NORTON ROBSON COOKE.
